CAR DOOR SUPPORT

Carl Lute, Hammond, Ind., assignor, by mesne assignments, to The Youngstown Steel Door Company, Cleveland, Ohio, a corporation of Ohio

Application February 3, 1934, Serial No. 709,562

17 Claims. (Cl. 16—99)

This invention relates to car doors and concerns itself primarily with sliding doors for railway freight cars adapted to be frictionally supported in open and closed positions.

5 It is an object of this invention to provide sliding doors for railway cars adapted to be frictionally supported in open and closed positions, the frictional supporting means including swinging cams.

10 A further object is to provide sliding car doors supported upon antifriction means for travel between open and closed positions and upon friction means embodying swinging cams whereby to relieve the antifriction means of the weight of the 15 doors in said positions.

A further object is to provide sliding doors frictionally supported in open and closed positions, the supporting means being so constructed as to obviate the need for actuating mechanism 20 for shifting the doors from said supporting means to rolling means utilized to support the doors during their travel.

25 A further object is to provide sliding doors antifrictionally supported upon tracks for travel between open and closed positions and frictionally supported in such positions by fixed and movable cams carried by said doors and tracks.

30 A further object is to provide sliding doors antifrictionally supported by means of ball and spacer units upon tracks for travel between open and closed positions and frictionally supported in such positions by means embodying swingable cams engageable with the spacers of said units whereby to avoid shifting of said units relative 35 to said doors.

35 A further object is to provide sliding doors antifrictionally supported upon tracks for travel between open and closed positions and supported in such positions by means including swingable cams capable of elevating said doors above the antifrictional supporting means.

40 Other objects will become clear as the description of the invention proceeds.

45 In the drawings forming part of this specification:

Figure 1 is a partial elevation of a railway car provided with doors embodying the invention, one of the doors being shown in closed position;

50 Figure 2 is a view similar to Figure 1, the door being shown in open position;

Figure 3 is a view similar to Figure 1, the door being shown in an intermediate position;

55 Figure 4 is a horizontal section taken on line 4—4 of Figure 1;

Figure 5 is a horizontal section taken on line 5—5 of Figure 1;

Figure 6 is a vertical section taken on line 6—6 of Figure 1;

Figure 7 is a vertical section taken on line 7—7 of Figure 1;

Figure 8 is a horizontal section taken on line 8—8 of Figure 1; and

Figure 9 is a horizontal section taken on line 9—9 of Figure 1.

10 Referring to the drawings, in which a preferred embodiment of the invention is illustrated, the numeral 10 designates a portion of a side of a railway house car. An opening is provided in the side of said car, the vertical margins of which 15

are defined by means of the front and rear door posts 11 and 12 and the lower margin of which is defined by the floor 13. A front stop angle and guard strip 14 is secured to the front door post 11 and a guard 15 is secured to the rear door post. 20

A track 16 is disposed below the door opening hereinabove defined and is maintained in desired position by means of a plurality of track supporting brackets 17 secured to a side sill (not shown) of the car.

25 The track 16 is adapted to support a door 18 for sliding movement in order to open and close the door opening provided in the car side. The door as illustrated may be formed of metal and

comprises a metallic panel 19 provided with horizontal corrugations 20 which merge at their ends 30

into vertical corrugations 21 and 22. The vertical corrugations 21 and 22 terminate as indicated at 23 and 24 above the lowermost horizontal corrugation 20, the terminals 25 and 26 of which lie 35

within the vertical corrugations. By means of the above described structure of the vertical and horizontal corrugations flat portions are provided 40

at the lower corners of the door for a purpose which will hereinafter appear.

45 The door is supported upon antifrictional means for movement relative to the track 16 between open and closed positions. In the illustrated embodiment of the invention the supporting means preferably takes the form of a plurality of balls 27 maintained in proper spaced relationship by means of a ball spacer 28 slidably supported upon the track 16 and movable with the balls. The balls 27 are adapted to be seated 50

within a ball runway 29 in rolling engagement therewith and in rolling engagement with the supporting track 16.

55 Brackets 30 and 31 are secured to the door upon the flat portions provided in the lower corners thereof. Each of these brackets, as clearly

shown in Figures 1, 6, 8 and 9, is so disposed as to overlap the terminal portions of the vertical and horizontal corrugations in order to close said corrugations. The bracket 30 is formed 5 with a downwardly opening pocket 32 within which a cam 33 is swingably mounted by means of a pin 34 extending through aligned openings in said bracket and in said cam. The bracket 31 is similarly formed and is provided with a pocket 10 35 within which is received a cam 36 swingably mounted therein by means of a pin 37 having bearing within the bracket and extending through an opening provided in the cam. The front and rear vertical walls 38 and 39 of the 15 pocket 32 are formed adjacent their lower edges with shoulders 40 and 41 adapted to cooperate with oppositely extending studs 42 and 43 formed on the cam 33 as will hereinafter appear. Similarly, the front and rear walls 44 and 45 of the 20 pocket 35 are provided adjacent their lower edges with shoulders 46 and 47 which may coact with oppositely extending lugs 48 and 49 provided on the cam 36. The walls 38 and 39 of the pocket 32 are connected at their upper edges by means of 25 a rib 50, while the walls 44 and 45 of the pocket 35 are connected by means of a rib 51.

The rear walls 38 and 45 extend downwardly, as clearly shown in Figures 6 and 7 of the drawings, below the track and, together with the 30 downwardly extending wing 52 of the ball runway 29, provide means preventing outward movement and disengagement of the door from the track. The bracket 30 is secured to the panel 19 of the door by means of rivets 53 which 35 also aid in securing the front edge sealing strip 54 to said panel. Adjacent its lower edge the sealing strip 54 is coped as indicated at 55 to permit easy assembly of the bracket 30 with the sealing strip 54. It will be clear from Figure 8 40 of the drawings that the sealing strip 54, together with the front wall 56 of the bracket 30, coact with the front stop angle 14 to exclude weather from the car.

The bracket 31 is secured to the rear margin of 45 the door 18 in part by means of rivets 57 which serve additionally to secure the rear edge sealing strip 58 and a buffer angle 59 to the door. The sealing strip 58, as clearly shown in Figure 9 50 of the drawings, coacts with the guard strip 15 secured to the rear door post 12 in order to exclude the weather from entering the car.

A pair of cams or supports 60 and 61 are secured preferably upon the track 16. The cam 60 is disposed adjacent the front stop angle 14 55 while the cam 61 is secured upon the track adjacent the rear vertical edge of the door when said door is in open position. The cam 60 is provided with a portion 62 inclined upwardly in the direction of closing movement of the door and a recessed portion 63 providing a shoulder 64. The fixed cam or support 61 is provided with a portion 65 inclined upwardly in the direction of opening movement of the door and a recessed portion 66 providing a shoulder 67.

65 The track 16 at a predetermined point thereof has secured thereto a stud 68 adapted to coact with the depending flanges 69 and 70 formed on the extensions 71 and 72 of the ball spacer 28. These extensions 71 and 72 are provided additionally with the upwardly extending abutments 73 and 74.

It is believed with the foregoing detailed description of the preferred embodiment of the invention that the operation thereof will be clear. 75 In Figure 1 of the drawings the door is illus-

trated in its closed position, in which, as will be apparent from Figures 6 and 7 of the drawings, the weight of the door has been removed from the balls 27 and is carried by the fixed cam or support 60, the extension 71 provided on the ball 5 spacer and the swinging cams 33 and 36. Similarly, in the open position of the door illustrated in Figure 2 of the drawings the fixed cam 61, the extension 72 of the ball spacer and the swinging cams, again provide frictional supports 10 for the weight of the door, thereby relieving the balls 27 of such weight.

To dispose the door upon the balls for easy movement from the closed to the open position it is only necessary to grasp the door by some 15 means such as the customary fixed handle and to exert a force upon the door in the opening direction thereof. This force will cause the swinging cams 33 and 36 to fulcrum upon the fixed cam 60 and the ball spacer extension 71 20 whereupon the door will be moved in the direction of opening travel and disposed in engagement with the balls for antifrictional movement. The door will then be moved to open position and as it approaches said position the 25 swinging cam 36 will engage the inclined portion 65 of the fixed cam 61 so as to slide upwardly upon said portion and be received within the recessed portion 66 behind the shoulder 67. During this sliding movement of the swinging cam 30 36 it is maintained against rotation by means of the engagement between the lugs 48 and 49 provided on the cam and the shoulders 46 and 47 formed adjacent the lower edges of the walls 44 and 45 of the bracket 31. In this position of 35 the swinging cam the shoulder 67 will prevent sliding disengagement of the cam from the fixed support 61. Substantially simultaneous with the sliding engagement between the swinging cam 36 and fixed cam 61 the swinging cam 33 will 40 engage the abutment 73 formed on the extension 72 of the ball spacer 28, causing said swinging cam to fulcrum upon said extension until engagement occurs between said cam and the rib 50 provided between the walls 38 and 39 at the 45 pocket 32 formed in the bracket 30.

The action of the swinging cams it will be evident will elevate the door so that the ball runway 29 will be out of engagement with the balls and the door will be frictionally supported 50 upon the extension 72 of the ball spacer and the fixed cam 61. It will also be apparent that inasmuch as the extension 72 is disposed upon the track the weight of the door, acting through the swinging cam 33, will maintain the ball spacer in 55 substantially fixed relationship with the track so as to prevent shifting of the balls relative to the door. In order to insure proper engagement between the swinging cam 33 and the abutment 73 of the ball spacer the stud 68 extending from 60 the track will engage the depending flange 70 provided on the extension 72, thereby limiting the movement of the ball spacer in the direction of opening travel of the door.

In the closing movement of the door the swinging cam 33 will slide upon the inclined portion 62 of the fixed cam 60 and subsequently drop into the recessed portion 63 behind the shoulder 64 provided on said fixed cam. Swinging movement of the cam 33 is prevented during this sliding movement by means of the engagement of the lugs 42 and 43 provided on the cam with the shoulders 40 and 41 formed on the walls 38 and 39 of the pocket 32. The swinging cam 36 will, during the closing movement of the door, over- 75

take the ball spacer 28 and through engagement of said cam with the abutment 74 will fulcrum upon the extension 71 of the ball spacer until engagement between said cam and the rib 51 occurs. At this time the door in its closed position is elevated above the balls and frictionally supported upon the fixed supports 60 and 71. The weight of the door upon the spacer extension 71 will maintain said spacer against movement upon the track while the engagement between the stud 68 and the depending flange 69 provided on the extension 71 will insure the fulcruming action of the swinging cam 36 upon said extension.

15 It is to be observed that in both the open and closed positions of the door the weight of the door acts through the pins 34 and 37 which are disposed in horizontally offset relationship to the points of engagement between the swinging and fixed supports in the direction of movement of the door. In view of this fact resistance is offered to the accidental shifting of the door in the opposite direction and the disposal of the weight of the door upon the balls.

25 It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car having a track and a sliding door, a ball runway for said door, a plurality of balls adapted to have rolling engagement with said runway and said track for supporting said door for antifrictional movement, a spacer adapted to be seated upon said track and associated with and maintain said balls in spaced relationship, means for elevating and frictionally supporting said door in the open and closed positions, thereby transferring the weight of said door from said balls to said means, and means engageable with said spacer in said door positions for preventing shifting of said balls along said track.

2. In a railway house car having a track and a sliding door, a ball runway for said door and secured thereto against rotation, a plurality of 50 balls adapted to have rolling engagement with said runway and said track for supporting said door for antifrictional movement, a spacer adapted to be seated upon said track and associated with and maintain said balls in spaced 55 relationship, means for frictionally supporting said door in open and closed positions whereby to relieve said balls of the weight of said door and other means engageable with said spacer in said door positions for preventing shifting of 60 said balls along said track.

3. In a railway house car having a track and a sliding door, a ball runway for said door and secured thereto against rotation, a plurality of 65 balls adapted to have rolling engagement with said runway and said track for supporting said door for antifrictional movement, a spacer adapted to be seated upon said track and associated with and maintain said balls in spaced 70 relationship, means for frictionally supporting said door in open and closed positions whereby to relieve said balls of the weight of said door and a stud projecting laterally beyond said track and engageable with projections formed on said spacer in said door positions for preventing 75 shifting of said balls along said track.

4. In a railway house car having a track and a sliding door, a ball runway substantially inverted V-shape in section adapted to be carried by said door, a plurality of balls seated in said runway and adapted to have rolling engagement therewith and with said track for supporting said door for antifrictional movement, a spacer adapted to be disposed upon said track and associated with and maintain said balls in spaced relationship and means for obtaining substantially fixed relationship between said spacer and track in the open and closed positions of said door to prevent shifting of said balls, said means comprising swinging cams adapted to be secured to said door adjacent the vertical edges thereof, one of said cams engaging and fulcruming upon said spacer in one of said positions of the door to elevate and dispose a part of the weight of said door upon said spacer and the other cam similarly cooperating with said spacer in the other position of said door for the purpose set forth.

5. In a railway house car having a track and a sliding door, antifriction means for slidably supporting said door upon said track, fixed and relatively movable supports adapted to be carried by said track, swinging cams adapted to be secured to said door adjacent the vertical edges thereof, said swinging cams engaging certain of said fixed and movable supports in predetermined positions of said door to elevate and frictionally support said door.

6. In a railway house car having a sliding door, antifriction elements for supporting said door, cams adapted to be swingably secured to said door adjacent the vertical edges thereof, supports carried by said car, one of said swinging cams fulcruming about an adjacent support at a predetermined position of the door to elevate and frictionally support a part of the door, the other of said swinging cams being slidably engaged with an adjacent support to elevate and frictionally support the remaining part of said door, said supports being provided with shoulders engageable with and preventing sliding disengagement of said swinging cams in said predetermined door positions.

7. In a railway house car having a sliding door, antifrictional elements for supporting said door, cams adapted to be swingably secured to said door adjacent the vertical edges thereof, supports carried by said car, one of said swinging cams fulcruming about an adjacent support at a predetermined position of the door to elevate and frictionally support a part of the door, the other of said swinging cams being slidably engaged with an adjacent support to elevate and frictionally support the remaining part of said door, said swinging cams having lugs engageable with shoulders provided on said door to limit swinging movement of said cams in one direction while permitting swinging movement thereof in the opposite direction.

8. In a railway house car having a sliding door, antifriction elements for supporting said door, cams adapted to be swingably secured to said door adjacent the vertical edges thereof, supports carried by said car, one of said swinging cams fulcruming about an adjacent support at a predetermined position of the door to elevate and frictionally support a part of the door, the other of said swinging cams being slidably engaged with an adjacent support to elevate and frictionally support the remaining part of said door, said fixed cams being provided with

shoulders engaging and preventing sliding disengagement of said swinging cams, said swinging cams having lugs engageable with shoulders provided on said door to limit swinging movement of said cams in one direction while permitting swinging movement thereof in the opposite direction.

9. In a railway house car having a sliding door, means for frictionally and antifrictionally supporting said door upon said car, said means comprising cams swingably mounted upon said door adjacent the lower corners thereof, antifriction elements for supporting said door for movement upon said car and shouldered supporting members carried by said car, said cams cooperating with certain of said supporting members in the open position of said door and with the remaining supporting members in the closed position of said door to elevate and frictionally support said door in elevated position, whereby the weight of said door is removed from said antifriction elements, one of said cams swinging about its supporting member as a fulcrum in the elevation of the door, portions of said cams lying behind said shoulders when said door is frictionally supported.

10. In a railway house car having a sliding door, means for antifrictionally and frictionally supporting said door upon said car, said means comprising cams adapted to be swingably mounted upon said door adjacent the lower corners thereof, antifriction elements adapted to support said door for movement upon said car and supporting members adapted to be carried by said car, said cams cooperating with certain of said supporting members in the open position of said door and with the remaining supporting members in the closed position of said door to elevate and frictionally support said door in elevated position, whereby the weight of said door is removed from said antifriction elements, one of said cams swinging about its supporting member as a fulcrum in the elevation of the door.

11. In a railway house car having a track and a sliding door, means for antifrictionally and frictionally supporting said door upon said car, said means comprising a plurality of balls adapted to be interposed between said track and door for supporting said door for antifrictional movement upon said track, a spacer associated with and maintaining said balls in spaced relationship, swinging cams adapted to be mounted upon said door adjacent the lower corners thereof, fixed supports adapted to be secured to said track and fixed supports carried by said spacer, said cams being engageable with the adjacent track and spacer supports in the open and closed positions of said door to elevate and frictionally support said door above said balls.

12. In a railway house car having a track and a sliding door, means for antifrictionally and frictionally supporting said door upon said car, said means comprising a ball runway for said door, a plurality of balls adapted to have rolling engagement with said runway and said track for supporting said door for antifrictional movement, a spacer adapted to be seated upon said track and associated with and maintain said balls in spaced relationship, swinging cams adapted to be secured to said door adjacent the vertical edges thereof, one of said cams engaging and fulcruming upon said spacer at a predetermined position thereof and the other of said cams engaging and fulcruming upon said spacer at another predetermined position thereof to elevate and dispose a part of the weight of said door upon said spacer, and means including

and disposed a part of the weight of said door upon said spacer.

13. In a railway house car having a track and a sliding door, means for antifrictionally and frictionally supporting said door upon said car, said means comprising a ball runway for said door, a plurality of balls adapted to have rolling engagement with said runway and said track for supporting said door for antifrictional movement, a spacer adapted to be seated upon said track and associated with and maintain said balls in spaced relationship, swinging cams adapted to be secured to said door adjacent the vertical edges thereof, one of said cams engaging and fulcruming upon said spacer at a predetermined position thereof and the other of said cams engaging and fulcruming upon said spacer at another predetermined position thereof to elevate and dispose a part of the weight of said door upon said spacer, and means projecting laterally beyond said track for determining said positions of said spacer.

14. In a railway house car having a track and a sliding door, means for antifrictionally and frictionally supporting said door upon said car, said means comprising a ball runway for said door, a plurality of balls adapted to have rolling engagement with said runway and said track for supporting said door for antifrictional movement, a spacer adapted to be seated upon said track and associated with and maintain said balls in spaced relationship, swinging cams adapted to be secured to said door adjacent the vertical edges thereof, one of said cams engaging and fulcruming upon said spacer at a predetermined position thereof and the other of said cams engaging and fulcruming upon said spacer at another predetermined position thereof to elevate and dispose a part of the weight of said door upon said spacer, and means carried by said door and cams for limiting the swinging movement of said cams.

15. In a railway house car having a track and a sliding door, means for antifrictionally and frictionally supporting said door upon said car, said means comprising a ball runway for said door, a plurality of balls adapted to have rolling engagement with said runway and said track for supporting said door for antifrictional movement, a spacer adapted to be seated upon said track and associated with and maintain said balls in spaced relationship, abutments provided on said spacer, swinging cams adapted to be secured to said door adjacent the vertical edges thereof, one of said abutments engaging a cam at a predetermined position of said spacer and the other of said abutments engaging a cam at a predetermined position of said spacer and causing said cams to fulcrum upon said spacer to elevate and dispose a part of the weight of said door upon said spacer.

16. In a railway house car having a track and a door, means for supporting said door for antifrictional movement upon said track, said means comprising a runway for said door, a plurality of balls adapted to have rolling engagement with said runway and said track, a spacer adapted to be seated upon said track and associated with and maintain said balls in spaced relationship, swinging cams adapted to be secured to said door adjacent to the vertical edges thereof, one of said cams being adapted to engage and fulcrum upon said spacer at a predetermined position thereof to elevate and dispose a part of the weight of said door upon said spacer, and means including

the other of said cams adapted to elevate and frictionally support the remainder of said door at said position.

17. In a railway house car having a track and 5 a door, means for supporting said door for anti-frictional movement upon said track, said means comprising a ball runway for said door, a plurality of balls adapted to have rolling engagement with said runway and said track, a spacer adapted 10 to be seated upon said track and associated with

and maintain said balls in spaced relationship, a swinging cam adapted to be secured to said door adjacent a vertical edge thereof, said cam being adapted to fulcrum upon said spacer at a predetermined position thereof to elevate and dispose 5 a part of the weight of said door upon said spacer, and means on said door and car cooperating to elevate and frictionally support the remainder of said door at said position.

CARL LUTE. 10
